BURNER FOR LIQUID FUELS

Palmiro Pulidori, Florence, Italy

Application February 15, 1933, Serial No. 656,784
In Italy February 27, 1932

1 Claim. (Cl. 158—28)

This invention relates to new and useful improvements in automatic pre-carburetting burners.

The object of the invention is to maintain the air and fuel proportions constant under all operating conditions and the carburetted mixture homogenous.

A preferred embodiment of the invention consists of a tubular body within which is disposed 10 a suitably perforated cross-head beam, within the longitudinal bore of which a diffuser is located. One portion of the perforated cross-beam—viz: one of the tubes—opens into the atmosphere, while the opposite end of the said 15 section opens towards the interior of the diffuser. The other portion of the cross-beam comprises a pipe or tube one end of which dips into a constant level reservoir, and the other end opens into the interior of the aforesaid diffuser. At a suitable 20 distance from this diffuser—and always within the body—is located a second diffuser, presenting an external surface in the shape of a truncated cone provided with helical vanes which are concentric with and contact the inner surface of 25 the admission cone of a third diffuser.

In the vicinity of the mouth of the third diffuser the aforesaid tube is provided with an annular passage. The liquid fuel is heated while flowing through said passage in order to be gradually conducted into the constant level reservoir 30 and is utilized forthwith, thus preventing the circulation of heated fuel through the tanks and the piping conveying the fuel to the burner and the formation of explosive mixtures.

Upon the burner body there are provided inlets for atmospheric air which, after passing through an annular chamber formed by the interior of the cylindrical body and the exterior of the third diffuser, joins the current of gaseous 40 mixture in a state of combustion.

The invention will be more clearly understood by referring to the following specification in conjunction with the drawing, which shows, solely by way of example, one practical embodiment of the 45 invention.

In this drawing:

Fig. 1 shows the device diagrammatically and in vertical section;

Fig. 2 shows the same device in cross section 50 on line A—B of Fig. 1;

Fig. 3 shows a variation of the device shown in Figure 2;

Fig. 4 shows a perspective of the diffuser.

According to the example shown, the device 55 consists of a reservoir *a* of any suitable shape, intended to be filled with liquid fuel up to a certain level which is maintained constant by well-known means. The reservoir *a* is suitably fixed to the tube *b* which constitutes the carburetter body. Through the tube *b* passes the air (in the

direction indicated by the arrows) for the aspiration, atomization and combustion of the liquid fuel contained in the constant level reservoir *a*.

In the interior of the tube *b* is arranged a cross-head beam *c* whose axis A—B coincides 5 with a diameter of the tube *b*.

The cross-head beam *c* carries three bores; one being longitudinal whose axis coincides with the axis X—X of the tube *b*; and two transverse and diametrically opposed, whose axes coincide 10 with the line A—B.

Within the longitudinal bore is arranged a diffuser *d*.

Into one of the vertical bores in the cross-head beam *c* extends a small tube *e* which opens at 15 one end into the interior of the diffuser *d*.

Into the diametrically opposite bore extends a small tube *f* which dips at one end into the liquid fuel contained in the constant level reservoir *a* and at the other end the tube *f* opens into the interior of the diffuser *d*.

At a convenient distance from the diffuser *d* and co-axially therewith is arranged a second diffuser *g* a perspective of which is shown in Fig. 4. The diffuser is a truncated cone the base of 25 which constitutes the inlet. Upon the external surface of the truncated cone shaped diffuser *g* a number of vanes *h* are suitably provided integrally with the extension of the inlet cone of a third diffuser *i*. The external surface of the latter is cylindrical and integral with the tube *b*. The diffuser *i* is provided with a recess *k*. The elements *g*—*h*—*i* form an integral and compact 30 whole rigid with the tube *b*.

The operation of the apparatus is as follows: 35

The air required for combustion flows through the tube *b* in the direction indicated by the arrows. A certain quantity of the air passes through the diffuser *d* and the remainder is distributed between two circuits in parallel, one 40 being constituted by the central port of the diffuser *g* and the other by the empty space *l*. The space *l*, which is annular in section, is formed by the external surface of the truncated cone shaped diffuser *g* and the internal surface of the inlet 45 cone of the diffuser *i*.

The air passing the diffuser *d* concurrently with the air passing through the diffuser *g* gives rise to three distinct phenomena: an aspiration of the fuel from the constant level reservoir *a* through the small tube *f*, the atomization of the fuel due to the violent encounter between air and fuel at right angles, and the aspiration of a certain quantity of atmospheric air drawn into the interior of the diffuser *d*.

The current of atmospheric air drawn into the interior of the diffuser *d* through the small tube *e* brings about a certain throttling of the current of air passing through the diffuser *d*, or a certain counter-pressure within the said diffuser.

This checking or throttling action brought about by the air aspirated from the atmosphere through the small tube *e* is proportional to the variations in operating conditions to which the air passing through the tube *b* is subjected and causes the proportionate discharge of the fuel aspirated through the small tube *f*.

The discharge of fuel is thus automatically checked, the checking action being progressive,

10 i. e., increasing with the increase of speed of the air passing through the tube *b* and, consequently, the diffuser *d*.

15 The device described realizes the condition of rendering the functioning of the apparatus automatic.

20 The second condition, indispensable in order to obtain the utmost efficiency of the apparatus, is fulfilled through the air and the fuel being mixed as indicated below, that is, by compelling all the 25 particles of air and of atomized fuel to participate in the phenomenon of combustion.

25 The portion of air passing through the tube *b* along the path indicated by the arrows and not passing through the diffuser *g* is expressly detoured and compelled to traverse the annular space *l*. Owing to the contour of the vanes *h* the air stream moves longitudinally with a whirling motion with respect to and in the direction of the axis X-X.

30 After passing through the passages formed by the vanes the air continues to move, gyrating around the axis of *b* and along the said axis in the direction shown by the arrows. The air encounters at a certain angle the mixture of air 35 and atomized fuel flowing out of the discharge cone of the diffuser *g*, compelling it to take on a rapid whirling motion. Although the fuel is finely atomized, in consequence of its bulk it spreads into the discharge cone of the diffuser *i* and becomes 40 intimately mixed (in said discharge cone) with the air flowing out of the annular space *l*.

45 In the modification shown in Fig. 3 the fuel drawn out of the constant level reservoir *a* through the small tube *f* instead of flowing into the interior of the diffuser *d* through a single aperture located diametrically opposite the small tube *e*, passes through a groove *m* which is cut externally around the diffuser *d*. The fuel is 50 drawn out of the groove *m* by the air flowing through the diffuser and through two or more apertures *n-n* communicating with the groove *m* in the wall of the diffuser *d* and opening into the interior thereof.

55 The necessary pre-heating of the fuel is obtained as follows:—The liquid fuel descends from a feeder—not shown in the drawing—located at a level higher than that of the apparatus. Through the small tube *o* the fuel flows into the passage space *p* where the heat developed by the combustion which takes place in the ignition chamber *q* is partly transmitted through the walls of the diffuser *i* and the annular space *r*.

60 On leaving this annular space, the heated fuel flows through the small tube *s* into the constant level reservoir *a*.

65 On the periphery of the tube *b* and communicating with the recess *k* are provided apertures *t*.

70 The fuel-air mixture issuing from the diffuser *g* enters the diffuser *i* whence it travels to the pre-combustion chamber *q*. The mixture may be ignited at this point.

75 The current of gaseous mixture undergoing combustion and issuing from the burner outflow

nozzle draws in through the said apertures a certain quantity of fresh atmospheric air which enters the recess *k* and, flowing thence through the annular space *r* unites with the gaseous mixture which is undergoing combustion.

80 The number of apertures *t* or the opening and closing of such apertures serves to regulate at will the current of fresh air drawn in from the atmosphere which, in turn limits the pre-heating of the fuel.

85 In operation, a blower is situated at the inlet end of the body *b*, opposite the combustion chamber. Air from the blower passing through the diffuser *d*, creates a suction which draws atmospheric air through *e* and preheated fuel from the reservoir *a* through *f*. The air and fuel are thus forcibly intermingled in *d*, then follow the direction of the arrows into the second diffuser *g* and through the helical vanes *h* whereby a whirling motion is imparted thereto as the air passes 20 into the combustion chamber. At the same time further atmospheric air is supplied to the combustion chamber through the opening *t*, annular chamber *k* and passage *r*.

90 It should be understood that the accompanying drawing shows but one example of the invention, whose constructional details may be varied without departing from the concept or from the characteristic features of the said invention; in fact, for instance, the annular space *r* might be formed 30 either by the adequate reduction of the external diameter of the diffuser *i* in correspondence with the recess *p* or by always providing for the adequate increase of the internal diameter of the tubular body *b* in correspondence with the recess 35 *p*.

Having now particularly described and ascertained the nature of my said invention and in what manner the same is to be performed, I declare that what I claim is:

95 A pre-carburetting burner of the character described, which comprises a tubular body connected to a compressed air supply, a cross beam disposed in said tube, said cross beam being provided with a central bore forming a diffuser, a liquid fuel reservoir associated with said tubular body, a conduit connecting said reservoir with the said bore, a second conduit connecting said bore with the outer atmosphere whereby the compressed air passing through said bore will lift 50 fuel from said reservoir through the first conduit and draw in air through the second conduit, a quantity of air passing outside the said cross beam, a second diffuser disposed in said tubular body and a third diffuser carrying said second 55 diffuser, said three diffusers being disposed coaxially inside said tubular body, said second diffuser being provided on its outside with helicoidal passage ways to impart a rotary movement to the fuel-air mixture issuing from the first diffuser, a 60 pre-combustion chamber communicating with the third diffuser, said mixture issuing into the fore-part of the said tubular body, means establishing communication between the said fore-part of the tubular body and the outer atmosphere, 65 the said fuel-air mixture issuing from the pre-combustion chamber drawing in fresh air through said means, and a fuel supply line connected with said reservoir disposed adjacent the said pre-combustion chamber to heat the fuel passing 70 through said line, the latter delivering the pre-heated fuel to said reservoir.
